DESIGN FOR A PHOTOGRAPHIC TRIPOD HEAD

Robert S. Gans, Birmingham, Mich., assignor
to Oxford Engineering Corporation, Oxford,
Mich., a corporation of Michigan

Application May 22, 1946, Serial No. 129,972

Term of patent 14 years

(Cl. D61—1)

To all whom it may concern:

Be it known that I, Robert S. Gans, a citizen
of the United States of America, residing in
Birmingham, in the county of Oakland, State of
Michigan, have invented a new, original, and or-
namental Design for a Photographic Tripod Head,
of which the following is a specification, refer-
ence being had to the accompanying drawing,
forming a part thereof, wherein:

Figure 1 is a side elevational view of a tripod
head, and

Figure 2 is a front elevational view thereof,
showing my new design.

I claim:

The ornamental design for a photographic tri-
pod head, substantially as shown.

ROBERT S. GANS.
